UNITED STATES PATENT OFFICE.

RICHARD PALMER GRIEVE, OF BOSTON, MASSACHUSETTS.

INTERNAL-COMBUSTION ENGINE.

1,345,169.

specification of Letters Patent. Patented June 29, 1920.

Application filed September 9, 1919. Serial No. 322,651.

To all whom it may concern:

Be it known that I, RICHARD P. GRIEVE, a citizen of the United States, and a resident of Chelsea, Boston, in the county of Suffolk and State of Massachusetts, have invented a new and Improved Internal - Combustion Engine, of which the following is a full, clear, and exact description.

This invention relates to new and useful improvements in internal combustion engines, and it pertains more particularly to a piston construction therefor.

In some types of internal combustion engines, there are two pistons, which are movable relatively to the cylinder and to each other, and it is the primary object of the present invention to improve the construction of pistons in these types of engines.

It is a further object of the invention to construct the internal combustion engine pistons in such a manner that one of said pistons is adapted to be protected by the other piston.

Engines of the two-cycle type have been constructed in the aforementioned manner, but it has been found that the upper or super-piston owing to its exposure to the continuous action of the burnt gases, has a tendency to superheat, and when in this condition acts to pre-ignite the fuel charge and produce a detrimental effect upon the efficiency of the engine.

It is a further object of the invention to construct a super-piston in such a manner that its radiating surface is greatly increased contiguous to the walls of the cylinder in order that the same may be more effectively cooled.

In addition to the advantageous results obtained by this increase of radiating surface, the skirt formed on the upper end of the main piston serves to strengthen and stiffen the same, thus serving to effectively prevent any distortion or warping incident to high temperatures which frequently occur. It is to be understood that the specific length of this skirt may be varied as desired without departing from the spirit of the invention.

With the above and other objects in view, reference is had to the accompanying drawings in which—

Figure 1 is a vertical sectional view of an internal combustion engine cylinder showing the pistons thereof in elevation;

Fig. 2 is a similar view showing the pistons in vertical section, and

Fig. 3 is a sectional view taken on the line 3—3 of Fig. 2.

Referring more specifically to the drawings, the reference character 5 designates the internal combustion engine cylinder, and said cylinder 5 is provided with an intake port 6, and an exhaust opening 7, which is controlled by means of a valve 8. In the present instance, the device comprises a main piston 9 and a supplementary or sub-piston 10, which latter is provided with a depending stem 11 adapted to pass through a sleeve 12 carried by the main piston 9. The main piston 9 and the sub-piston 10 are provided with piston rings 13 and 14, respectively, for the purpose of providing a gas-tight joint between the pistons and the walls of the cylinder.

As best shown in Fig. 2, the main piston 9 has its upper end reduced, as at 15, and the upper end of said reduced portion is provided with an annular, angular wall 16. The sub-piston 10 is provided with an annular depending flange or skirt 20, the upper portion of said skirt being thickened as at 21, to provide an angular wall 22 adapted to coincide with the annular, angular wall 16 of the main piston 9 when its reduced portion 15 is received therein. The depending flange 20 is provided around its periphery with a plurality of grooves 26, and said grooves 26 are adapted to communicate, near the upper end of the sub-piston 10, with an annular groove 27, transverse grooves 28 passing through the thickened portion 21 of the annular flange or skirt 20, and forming means establishing communication between the interior of the skirt 20 and the groove 27, and thence with the interior of the cylinder 5 in the compression space thereof.

As best seen in Fig. 3, it will be noted that the grooves 26 and 28 are equi-distantly spaced about the peripheral face of the sub-piston 10 in order that the gas be uniformly distributed within the cylinder with greater facility.

The operation of the device is as follows:

Upon the power stroke of the piston, both the main piston 9 and the sub-piston 10 move downwardly into the cylinder 5 under the influence of the expanding gases contained in the cylinder. After the two pistons 9 and 10 have traveled through a por-

tion of the cylinder in unison, the movement of the sub-piston 10 is retarded by a suitable mechanism (not shown), thus allowing the main piston 9 to separate therefrom.

5 As further movement of the piston 9 takes place, the shoulder 30 thereof opens the intake port 6 for the purpose of taking in a fresh charge of explosive mixture.

As the main piston 9 starts upwardly on 10 the compression stroke, the fresh charge taken into the cylinder is compressed between said pistons from whence it passes around to the upper face of the sub-piston 10 by means of the by-passes formed by the 15 grooves 26 and 28, the last-mentioned by-pass permitting all of the gases between the two pistons moving to the upper face of the sub-piston 10, as the reduced portion 15 of the main piston passes into the depending 20 annular flange or skirt 20. The two pistons 9 and 10 now move upwardly of the cylinder until the compression of the explosive charge is complete, whereupon said compressed charge is ignited and the above- 25 described operation repeated.

Having thus described the invention, what is claimed as new is:

1. In an internal combustion engine, a cylinder, a piston having a reduced end and 30 slidably mounted in said cylinder, a second

piston mounted between the first-mentioned piston and one end of said cylinder, an annular flange integral with the second-mentioned piston and adapted to receive the reduced end of the first-mentioned piston and 35 provided with a series of circumferentially arranged by-passes adapted to establish communication between the interior of said annular flange and the exterior of the piston, and means for controlling the relative 40 movement of said pistons.

2. In an internal combustion engine, a cylinder having an enlarged upper portion, a piston movable with respect to said cylinder, a second piston movable relatively to 45 said cylinder and said first-mentioned piston, and an annular flange carried by the second-mentioned piston and adapted to engage a reduced end of the first-mentioned piston, said annular flange having radially 50 arranged passages passing therethrough adapted to establish communication between the interior of said annular flange and the enlarged portion of said cylinder, substantially as described.

RICHARD PALMER GRIEVE.
